(57) **CLAIM**

The ornamental design for a red light therapy knee pad, as shown and described.

DESCRIPTION

FIG. 1 is a front perspective view of a red light therapy knee pad, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is a front perspective view showing the red light therapy knee pad in a use state; and,

FIG. 10 is an enlarged detail view of area 10 in FIG. 2. The evenly dashed broken lines in FIGS. 1, 3, and 5-9 depict portions of the red light therapy knee pad that form no part of the claimed design. The thick dot-dash broken lines in FIGS. 1-4 and 9 depict stitching. The regular thickness dot-dash broken lines in FIGS. 2 and 10 depict the bounds of the enlarged views that form no part of the claimed design.

1 Claim, 10 Drawing Sheets
